CLAIM

The ornamental design for a neck care pillow device, as shown and described.

DESCRIPTION

FIG. 1 is a perspective view of a neck care pillow device showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is another perspective view thereof; and,

FIG. 9 is another perspective view thereof; the neck care pillow device shown as used.

The broken line disclosure is understood to be for illustrative purposes only and forms no part of the claimed design.
